UNITED STATES PATENT OFFICE.

ALFRED L. KRONQUEST, OF CHICAGO, ILLINOIS, ASSIGNOR TO CONTINENTAL CAN COMPANY, OF SYRACUSE, NEW YORK, A CORPORATION OF NEW YORK.

DETACHABLE CLOSURE FOR CONTAINERS.

1,355,151.

Specification of Letters Patent.

Patented Oct. 12, 1920.

Application filed May 25, 1920. Serial No. 384,120.

To all whom it may concern:

Be it known that I, ALFRED L. KRONQUEST, a citizen of the United States, residing at Chicago, in the county of Cook, 5 State of Illinois, have invented certain new and useful Improvements in Detachable Closures for Containers, of which the following is a description, reference being had to the accompanying drawing and to 10 the figures of reference marked thereon.

The invention relates to new and useful improvements in removable closures for containers, and more particularly to a container wherein the closure may be released by the 15 prying out of a retaining member.

An object of the invention is to provide a closure for containers of the above character wherein the pry-out retaining member is so disposed that the flange on the closure 20 may be rolled around said retaining member and the flange on the container body thereby pressed into sealing contact with the flange on the closure and the sealing material.

25 A further object of the invention is to provide a pry-out member of the above character wherein the ends are reversely tapered so as to overlap, thus forming substantially a continuous retaining member, and at the 30 same time, providing a construction wherein one end of the retaining member is readily accessible for prying the same out to release the closure from the container body.

These and other objects will in part be 35 obvious and will in part be hereinafter more fully disclosed.

In the drawings:—

Figure 1 is a vertical sectional view 40 through a portion of a container embodying my improvements;

Fig. 2 is a side view of the same with a part of the flange of the closure broken away to show the accessibility of one end of the pry-out member;

45 Fig. 3 is a perspective view of the pry-out retaining member, and

Fig. 4 is similar to Fig. 2 but showing the ends of the pry-out member slightly separated through the insertion of the tine 50 of a fork or the like for the prying out of the retaining member to release the closure from the container body.

The invention is directed broadly to a container, preferably formed of metal which 55 includes a cylindrical body portion and a

closure for each end thereof. One of the container ends is secured to the body portion by means of a pry-out retaining strip or wire, while the other container end is secured to the body portion by double seaming. The end having the pry-out retaining member is preferably applied at the factory by the manufacturer of the container, and after the container has been filled, then the other end is applied, and joined by a double 60 seam to the container body by the packer.

The container body is provided with a horizontally extending flange and the detachable closure or closing end is secured thereto by a retaining wire or strip placed against the under face of the flange on the can body, and the flange on the container end is rolled around said retaining wire so as to force the wire into contact with the lower face of the flange on the container 75 body and draw the flange on the closing end against the packing material placed between the flanges.

Referring more in detail to the drawings, I have shown my improvement as applied 80 to a container consisting of a body portion 1, one end of which is closed by a closure end 2 which is rolled into the ordinary double seam, while the other end of the container body is closed by a detachable closure 85 end 3. As above noted, the end 3 is first attached to the container body and this may be done by the manufacturer of the container. After the container is filled, then the end 2 is applied and secured to the body 90 portion by a double seam, and this may be done by the packer.

The body portion 1 is provided with a horizontally extending flange 4. The closure end 3 is provided with a recess 5 forming a vertical wall 6 which fits within the end of the container body. Said closure end 3 also is provided with an outwardly extending flange 7. A suitable packing indicated at 8 may be placed between the flanges 4 and 7. After the closure end has been inserted in the container body, then the retaining wire or strip 9 is placed about the end of the container body and against the under face of the flange 4. This retaining wire is preferably round in cross section, and the ends thereof are reversely tapered as indicated respectively at 10 and 11. When in place, these ends overlap as shown in Fig. 2. The flange 7 of the closure end is rolled around this 110

retaining member 9 as clearly shown in Fig. 1. This may be done by the ordinary seaming roll. The free edge 12 of the flange is spaced from the wall of the body portion of the container a distance slightly less than the diameter of the retaining member 9, and as a result, during the rolling action which carries the flange of the closure end around said retaining wire 9, said wire 9 is pressed firmly against the under face of the flange 4 and at the same time, the flange 7 is drawn down into sealing contact against the sealing material between the two flanges. Thus it is that a sealed joint is formed between the closure end 3 and the body of the container.

When it is desired to remove this detachable closure end 3, the tine of a fork or the like indicated in Fig. 4 at 13 is inserted underneath the extreme free end 14 of the retaining member 9, and by forcing the tine of the fork between the overlapping ends 10 and 11, one end of the retaining member 9 will be forced out through the space between the free edge 12 of the flange of the closure end and the side wall of the container body. It will be noted that this extreme end 14 is at the lower side of the retaining pry-out wire as viewed in Fig. 2, and is therefore exposed so as to readily permit the insertion of the tine of the fork between the ends of the pry-out retaining member.

The flange of the closure end will be unrolled sufficiently to permit the retainer wire 9 to be pried out. After the wire has been removed, then the closure end may be readily removed from the can body, as the diameter of the free edge 12 of the flange 7 is less than the extreme outer diameter of the flange 4.

It is obvious that minor changes in the details of construction and the arrangement of the parts may be made without departing from the spirit of the invention as set forth in the appended claims.

Having thus described the invention,

what I claim as new and desire to secure by Letters-Patent, is:—

1. A container comprising a body portion having a flange extending outwardly therefrom, a closure end for closing one end of the body portion, said closure end being adapted to fit within the end of the container body and having a flange extending outwardly over the flange on the container body, a suitable packing arranged between said flanges, a pry-out retaining member disposed beneath the flange on the container body, said flange on the closure end being rolled around said pry-out retaining member a sufficient distance so as to force said pry-out retaining member against the under face of the flange on the container body and thereby draw the flanges on the closure end and the container body into sealing contact. 65

2. A container comprising a body portion having a flange extending outwardly therefrom, a closure end for closing one end of the body portion, said closure end being adapted to fit within the end of the container body and having a flange extending outwardly over the flange on the container body, a suitable packing arranged between said flanges, a pry-out retaining member disposed beneath the flange on the container body, 70 said flange on the closure end being rolled around said pry-out retaining member a sufficient distance so as to force said pry-out retaining member against the under face of the flange on the container body and thereby draw the flanges on the closure end and the container body into sealing contact, the ends of said pry-out retaining member being reversely tapered so that the extreme end of one tapered portion is exposed whereby the 75 implement may be readily inserted between the ends of said pry-out retaining member for prying out one end of said retaining member and thus releasing the closure end. 80

In testimony whereof I affix my signature. 90

ALFRED L. KRONQUEST.
